CONCEALED BED CONSTRUCTION

Edward George Hirst, Leaside, Ontario, Canada

Application October 18, 1950, Serial No. 190,773

11 Claims. (Cl. 5—140)

1

Introduction

The present invention relates to improvements in a concealed bed construction. This application is a continuation-in-part of application Serial No. 673,556, filed May 31, 1946, which is now abandoned.

Concealed beds of the type to which the invention relates consist essentially of a collapsible bed which, when not in use, may be folded and concealed within a receptacle. The present invention aims to provide an improved construction of a bed of this nature wherein the bed and receptacle form a single unit which is easily transported and may be easily moved from one location to another. The present combined bed and receptacle unit is simple both in design and in operation and eliminates the use of counterweights and counterbalancing springs making the unit compact and especially adaptable for use in apartments, hotels, cottages or other places where floor space is a problem. The compact folding of the bed into the receptacle also allows the unit to become an attractive piece of furniture as well as an article of utility making it adaptable for use as an occasional bed in offices, plants, or other places where an ordinary bed or couch would be impractical. The construction of this unit is such that it may be placed against the wall of a room or in a recess so as to occupy the minimum of floor space.

Accordingly, the present invention is embodied in a concealed bed construction comprising in combination with a receptacle, a bed frame mounted within the receptacle so as to pivot about a longitudinal axis of the frame intermediate the ends on the free ends of links pivoted within opposite ends of the receptacle. The movement of the side of the bed frame adjacent to the receptacle is guided in an upward and arcuate path whereby the bed frame can be swung on the links to a vertical position within the receptacle or to a horizontal extended position placing the bed in position for use outside of the receptacle. The linkage between the bed frame and receptacle is such that the swinging movement can be readily accomplished without the use of counterbalancing weights or the like.

One of the features of the present unit is that the bed frame is provided with collapsible head and footboards that are operated by linkage through the movement of the bed frame about the central pivot.

A further feature consists in providing collapsible legs pivoted to the side of the bed frame

2

remote from the receptacle that are operated by linkage associated with the links supporting the bed frame so as to collapse and extend with the closing and opening movement of the bed respectively.

A still further feature is embodied in the preferred construction of the receptacle which includes a pair of substantially centrally divided doors that are mounted in the receptacle so as to fold down vertically beneath the bed frame when the bed is opened and fold up vertically to close off the front of the receptacle when the bed is in concealed folded position within the receptacle. Linkage is provided between the doors and the bed supporting linkage so that the doors are held up in a partially open position until the bed frame has been unfolded and also raises the doors to a partially closed position when the bed is swung into the receptacle. This ensures that the doors can not fall or fold over the feet of anyone unfolding or folding the bed as well as eliminating the necessity of having to stoop and pull the door up from the floor when the receptacle is being closed.

Having thus generally described the nature of the invention particular reference will be made to the accompanying drawings illustrating a preferred construction of a concealed bed unit constructed in accordance with the present invention and in which:

Figure 1 is a front view in perspective elevation of a concealed bed unit constructed in accordance with the invention.

Figure 2 is a sectional view of Figure 1 along the line 2—2.

Figure 3 is a front view in perspective elevation of the construction shown in Figure 1 with the frame in open position.

Figure 4 is a front view of a portion of the construction shown in Figure 3, with the bed frame in the closed position and the doors of the receptacle open.

Figure 5 is a sectional view in plan of Figure 4 along the line 5—5.

Figure 6 is an end view of the construction shown in Figure 1 with the end of the receptacle removed to show the relative position of the closed bed frame and associated linkage within the receptacle.

Figure 7 is a detail view of a portion of Figure 6 along the line 7—7 to illustrate the construction in more detail.

Figure 8 is an end view corresponding to Figure 6 with the end of the receptacle removed to

illustrate the relative positions of bed frame, linkage and receptacle doors when the bed is opened.

Figure 9 is a sectional view of Figure 8 along the line 9—9 illustrating the head and foot rail locking arrangement in more detail.

Figure 10 is an enlarged detail view of the head and foot rail catch to illustrate the preferred construction more clearly.

Figure 11 is a sectional view of Figure 8 along the line 11—11 to illustrate the folding arrangement and operating linkage for the collapsible head and footboards.

Figure 12 is a sectional view corresponding to Figure 11 showing the collapsible headboard in the folded position.

Figure 13 is an enlarged detail view of the sliding pivotal connection between the headboard operating arm and the main supporting link.

Figure 14 is a diagrammatic view of the bed frame supporting linkage, receptacle door supporting and opening arm, and the associated safety closure cam arm as it appears in the folded position within the receptacle.

Figure 15 is a diagrammatic view corresponding to Figure 14 with the receptacle doors partially opened.

Figure 16 is a diagrammatic view corresponding to Figure 15 with the receptacle doors completely open and the bed frame completely opened.

Figure 17 is a diagrammatic view corresponding to Figure 16 with the bed frame partially closed within the receptacle to illustrate the initial door opening action of the door supporting lever arm.

Figure 18 is an enlarged detail view of one of the door supporting and opening lever arms.

With particular reference to Figures 1 and 2 of the drawings, a preferred construction of a concealed bed unit in accordance with the present invention is illustrated as comprising a substantially rectangular receptacle or cabinet 10 containing the collapsible bed and associated mechanism.

The receptacle 10 is made up of a steel inner frame 12 over which is mounted the cabinet structure proper consisting of a top panel 14, side panels 16, and a back panel 18 which are joined and supported at the corners by rear posts 20 and front posts 22. The panels and posts can be made of any suitable material, for example, wood, or plywood and are preferably assembled so that the receptacle may be easily taken down, if necessary, in moving or to facilitate the entry of the unit through a small doorway or window.

The front wall of the receptacle is made up of a two-piece door divided into hinged panels 24, 26 which open outwardly at the central hinging point indicated at 28 and fold vertically downwards. The top door panel 24 includes rollers 30 at each side adjacent the upper edge which are engaged with and ride in slotted grooves 32 provided in each of the front receptacle posts 22. The top panel 24 is hingedly mounted on the top of the lower panel 26 by means of suitable spring hinges 27, see Figure 2, and the lower panel 26 is mounted on a lower frame member 13 of the inner frame 12 by means of hinges 34. As is shown in Figure 14, a filler block 15 is secured to the inner face of the frame member 13 and the hinges 34 are secured to the filler block. With this arrangement the door panels 24, 26, when pulled outwardly by the handle 35 attached to the panel 24, fold outwardly and descend vertically with the travel of the upper edge of the panel 24 guided by the engagement of the rollers 30 in the grooves 32 of the posts 22. The particular hinging ar-

rangement of the bottom panel 26 to the frame member 13 provides a clearance space for the toes of anyone opening the doors. Means associated with the linkage of the bed supporting mechanism is adapted to support the partially folded doors clear of the floor before the bed is opened, as is shown in Figure 17, and will be described in more detail later.

Bed frame and linkage

The bed frame of the unit consists essentially of longitudinal side members 40, 41 and end members 42, 43 forming a rectangular bed frame on which there are supported springs 44.

10 The longitudinal side member 40 adjacent the receptacle when the bed is opened is connected to the end frame members 42, 43 by means of castings 45 at each end of the frame. The castings 45 also serve as supports and bearings for 15 the axles of a pair of roller guide wheels 47 which are thus rotatably mounted on the end frame members 42, 43 (see Figure 7).

The bed frame is mounted for swinging pivotal movement into and out of the receptacle 10 by 20 means of a pair of main supporting links 50. One end of each of the links 50 is pivotally connected by means of suitable brackets 51 to a lower frame member of the inner frame 12 at each side of the receptacle. The links 50 are also pivotally connected adjacent the other ends to the end bed frame members 42, 43 intermediate the ends of these members so that the bed frame is adapted to pivot about a longitudinal axis. A pair of 25 flanged members 57, 59 are secured to the frame members 11 and 17 of the inner frame 12 at each end of the receptacle with their flanges opposed to form a guide track 60. The guide wheels 47 mounted on the bed frame are adapted to travel on the flanges of the members 57, 59 in the guide track 60 so that the inner edge of the bed frame relative to the receptacle is guided in a vertical and partially arcuate path when the frame is pivoted about the supporting links 50.

30 A side mattress board 70 is mounted on the longitudinal side member 40 and a headboard having a lower portion 72 and an upper portion 71, and a footboard having a lower portion 74 and an upper portion 73 are secured to the mattress board 70 and the end frame members 42, 43 at opposite 35 ends of the frame so as to form the casement of the bed adapted to retain the mattress in position. The upper portions 71, 73 of the headboard and the footboard are hinged to the lower portions 72, 74 so that they may be folded inwardly when 40 the bed is folded so as to automatically lock the mattress and bed clothing in position as the bed is swung into the closed or concealed position.

45 With reference to the folding of the upper head and footboard portions 71, 73, the following description deals specifically with the headboard portions 72, 71, but it will be understood that the footboard portions 74, 73 operate in a similar manner. Referring particularly to Figures 11, 12 and 13 of the drawings, the upper headboard portion 71 is hingedly mounted on the lower portion 72 as indicated at 75 so that it can be folded inwardly only.

50 A sliding link 80 is pivotally connected at one end to the main supporting link 50, see Figure 13, so that the movement of the link 50 is transmitted to the link 80 when the bed frame is swung into or out of concealed positioned. A spring 81 is provided to take up any slack in the movement. The link 80 is supported for slidable movement on the 55 lower headboard portion 72 by means of a bracket

84, and is pivotally connected to a hinged link 86 mounted on the upper headboard portion 71. A slide plate 88 is provided on the headboard portion 72 beneath the pivotal connection between the links 80, 86. With this arrangement the outward swinging of the bed frame moves the link 50 so as to push the link 80 upwards so as to unfold the headboard portion 71 (see Figure 11). The inward movement of the bed frame moves the link 50 in the opposite direction so as to pull the link 80 downwards folding the headboard portion 71 inwards (see Figure 12).

In order to safeguard against the possibility of the headboard portions 71, 72 and footboard portions 73, 74 being folded accidentally when the bed is opened, say for example, by someone leaning or sitting on the bed, safety catches 90 are provided that automatically retain the headboard portions in the erected position and release them when the bed is closed. The safety catches 90 are positioned at each end of the receptacle 10 and are pivotally mounted on the vertical inner frame members 17 as is shown in Figure 9. Each of the catches 90 are preferably formed so as to have a concave shape in general cross-section, see Figure 10, so as to minimize the actual bearing surface coming into contact with the bearing plates 94 mounted on the headboard portions 71, and footboard portions 73.

The catches 90 are each actuated through rods 96 which are pivotally connected to and extend between each catch 90 and one end of lever arms 98 which are pivotally mounted on diagonal supporting members 19 of the inner frame 12 at each end of the receptacle. A spring 100 is provided between each of the catches 90 and the end of each of the rods 96 so as to give the locking movement resiliency. The other end of each of the lever arms 98 are adapted to be contacted by the roller guide wheels 47 at the end of their upward and outward travel when the bed is opened so that the connecting rods 96 are pulled downwards bringing the catches 90 into engagement with the upper edges of the head and footboards. A spring 120 is provided on each of the catches 90 so that release of the connecting rods 96 by the closing of the bed causes the catches 90 to swing upwards and away from the head and footboards and allows them to fold as previously described.

A pair of supporting legs 102 are pivotally mounted, one on each of the end bed frame members 42, 43 adjacent the longitudinal side frame member 41. These legs 102 are automatically swung down and refolded by connecting links 122 that are pivotally connected to the legs 102 and the main supporting links 50. The pivotal connections between the legs 102 and the side frame members 42, 43 are off centre relative to the centre line of the legs and the pivotal connections between the legs 102, and the links 122 are also off center so as to eliminate any possibility of the linkage sticking when the legs are folded parallel to the side frame members when the bed is closed.

The upper and lower door panels 24, 26, are prevented from folding completely down prior to the unfolding of the bed frame by means of a pair of spaced apart door supporting lever arms 130. Each of the lever arms 130 are pivotally mounted at one end to the bed frame end members 42 and 43 and are prevented from falling loosely by means of lengths of chain 132 secured to the lever arms 130 and the respective end members 42, 43. As is shown in detail in Figures 14, 15, 16, 17 and 18 the supporting lever arms 130

operate in the following manner. When the doors, 24, 26 are opened, the lever arms fall against the lower door portion 26, between the portion 26 and the upper portion 24. As the doors are lowered, the lever arms 130 descend to the limit of the chains 132 and thus the folded door portions are supported in a sufficiently low position to allow the bed to be opened but also sufficiently high relative to the floor so as to provide clearance for the feet of the person opening the bed. When the bed frame is swung about the supporting links 50 to open the bed the upward movement of the inner end of the bed frame members 42, 43, lowers and withdraws the supporting arms 130 so that the doors 24, 26, fold flatly against the floor as is shown in Figure 16. Conversely, when the bed is again swung about the links 50 to close the bed into the receptacle the lever arms 130 again raise the folded doors 24, 26, into the intermediate position so that they may be easily raised into their full extended closed position. It has been found, that due to the resilient hinging between the door portions 24, 26, and the present lever arm arrangement that very little effort is required to raise or lower the doors 24, 26, and that no locking mechanism is necessary to secure the doors in the closed position.

In order to ensure that the door portions 24, 26, do descend when the bed is opened, a pair of safety cam arms 140 are provided which follow the upper edge of the door portion 24 as it descends but do not contact the door unless the door sticks. These cams 140 are pivotally mounted at each end of the bed frame to the main supporting links 50 and are shaped so that the inner free ends of the cams travel between the axles mounting the guide wheels 47 and protruding studs 142 one of which is secured to each of the end bed frames 42, 43. The outer ends of the cams 140 adjacent the doors are each provided with a rubber roller 144. With this arrangement, the swinging movement of the bed frame about the links 50 as well as the forward and downward movement of the links 50 actuates the cam rollers 144 into an arcuate path. The arcuate path extends outwardly over the top edge of the door portion 24 and then downward following the travel of the door as it is lowered by the action of the lever arms 130. When the bed is closed the reverse movement of the bed frame and the supporting links 50 actuate the safety cam arms 140 upwardly in an arcuate path so as to move them away from the top door portion 24 and into the receptacle 10, as is shown in Figure 14.

In use, when the bed is to be opened, the handle 35 is pulled outwardly causing the door portions 24, 26, to fold outwardly and descend, the top edge of the door 24 being guided by the slots in the front posts 22. When the doors are lowered sufficiently to allow for the opening of the bed the lever arms 130 are supporting their weight and will continue to do so until the bed is opened. To open the bed it is grasped adjacent the upper edge and pulled outwardly. This action causes the bed frame to swing about its pivotal connection with the supporting links 50 and simultaneously causes the links 50 to pivot outwardly from the connection with the receptacle frame 12. Since the inner edge of the bed is restrained and guided by the engagement of the guide wheels 47 with the track 60, the inner edge of the frame moves upwardly and outwardly as the bed pivots and swings bodily to the horizontal

position. Simultaneously with this swinging motion of the bed frame, the head 71 and foot-board portions 73 are unfolded by the linkage 80, 86, and the legs 102 are unfolded into their supporting position by the links 122. The doors 24, 26, are completely lowered through the actions of the lever arms 130 and the headboard portion 71 and the footboard portion 73 locked in erected position by the retaining catches 98.

To close the bed, the lifting of the outer edge of the bed frame pivots the frame about the links 50 and the associated linkage folds up the legs and head and footboards so that the bed is folded compactly within the receptacle 48. As the doors 24, 26, have already been lifted by the lever arms 130 to the partially closed position, an upward pull on the handle 35 raises them to the point where the resilient hinges act to bring the door portions into vertical alignment and complete the receptacle closure.

I claim:

1. In a foldaway bed construction, a receptacle having an open front, a supporting frame within said receptacle, a rectangular bed frame having longitudinal side frame members connected by transverse end frame members, a guideway mounted on said supporting frame adjacent each end of said receptacle, a guide member carried by one end of each said bed frame end member slidably engaging said guideways, said bed frame being pivotally connected to said supporting frame by means of a pair of spaced apart elongated supporting links having their lower ends pivotally connected to said supporting frame adjacent said guideways and being pivotally connected adjacent their upper ends to said transverse bed frame end members beyond the centres of said members with respect to said guide members so as to constitute a pivotal axis extending longitudinally of said bed frame, whereby said bed frame is adapted to be swung about said longitudinal pivotal axis from a position within said receptacle wherein the bed frame is in parallel vertical alignment with said receptacle to a horizontal position exteriorly of said receptacle, the travel of the inner bed frame members adjacent said receptacle being guided by said guideways in a vertical upward and arcuate outward path when said bed frame is swung about said pivotal axis so as to extend said bed frame from said receptacle and in an arcuate inward and vertical downward path when said bed frame is swung into said receptacle.

2. In a foldaway bed construction, a receptacle having an open front, a bed frame having longitudinal side members connected by transverse end frame members, guideways arranged adjacent each end of said receptacle, guide members carried by one end of said bed frame end members slidably engaging in said guideways, said bed frame being pivotally connected thereto by means of a pair of spaced apart supporting links having their lower ends pivotally connected to said receptacle and being pivotally connected adjacent their upper ends to said transverse bed frame end members beyond the center of said members relative to said guide members so as to constitute a pivotal axis extending longitudinally of said bed frame, supporting legs pivoted at their upper ends to the ends of said transverse bed frame end members remote from said guide members, connecting links having one end pivotally connected to each of said legs and the other end to each of said supporting links whereby said bed frame is

adapted to be swung about said longitudinal pivotal axis from a vertical position within said casing to a horizontal extended position, the travel of the longitudinal bed frame member adjacent said guide members being guided by said connection with said guideways, said linkage between said pivotal legs and said supporting links effecting the movement of said legs between the collapsed and extended position as said frame is swung from a vertical to a horizontal position.

3. In a foldaway bed construction, a receptacle having an open front, a bed frame having longitudinal side frame members connected by transverse end members, said bed frame being pivotally connected to said receptacle by means of a pair of spaced apart supporting links having their lower ends pivotally connected to said receptacle adjacent the base thereof and being pivotally connected adjacent their upper ends to said transverse frame end members so as to constitute a pivotal axis extending longitudinally of said bed frame, guideways arranged in said receptacle adjacent each end thereof, guide members carried by one end of each of said bed frame end members engaging in and supported by said guideways adapted to guide the movement of the inner edges of said bed frame when swung on said supporting links about said pivotal axis between a vertical position within said receptacle to a horizontal extended position, supporting legs pivoted at their upper ends to the ends of the transverse end members of said bed frame remote from said guide members, a pair of connecting links each having one end pivotally connected to each of said first named supporting links with the other end pivotally connected to one of said legs, head and footboard members mounted on the transverse ends of said bed frame, foldable members hingedly secured to said head and footboard members, and connecting links pivotally connecting said head and footboard foldable members and the upper ends of said first named supporting links, whereby relative movement of said supporting links and said bed frame effects the movement of said head and footboard foldable members and said pivotally mounted legs from a collapsed to an extended position when said bed frame is swung from a vertical to a horizontal position.

4. A device as claimed in claim 3, in which said receptacle is provided with a closure for said open front to conceal said bed frame when swung within said receptacle, said closure comprising a lower door panel section extending longitudinally across said receptacle and hingedly connected adjacent to the bottom of said receptacle, an upper door panel section extending longitudinally across said receptacle and being hingedly connected to said lower panel section, guide means on said receptacle and means on the upper edge of said upper door panel section engageable in said guide means, said hinged connection between said upper and lower panels being resiliently biased whereby said panels are self-supporting in the extended vertical position forming a closure for the front of said receptacle.

5. In a foldaway bed construction as claimed in claim 3, retaining means adapted to retain said head and footboard foldable members in extended position, said retaining means comprising, a pair of catch members pivotally mounted on said receptacle one adjacent each end thereof, resilient means between each of said catches and said receptacle adapted to normally maintain said

catches in inoperative position, a lever arm pivotally mounted adjacent each end of said receptacle and having one end disposed in the path of said bed frame guideways, and connecting links between the other ends of said lever arms and said catches, whereby the final movement of said bed frame from vertical to horizontal position is adapted to move said bed frame guide means into contact with said lever arms and said movement is transmitted through the last mentioned connecting links to move said catches into retaining contact with said head and foot-board foldable members.

6. A foldaway bed construction as claimed in claim 5, wherein each of said retaining catches is formed so as to be of concave shape in general cross-section, the lower arcuate portion of said concave shape constituting the bearing surface of said catch adapted to engage with said foldable head and footboard members.

7. A foldaway bed construction comprising, a receptacle having an open front, a bed frame having longitudinal side frame members connected by transverse end frame members, guideways arranged adjacent each end of said receptacle, guide members carried by each of said end bed frame members slidably engaged in said guideways, said bed frame being pivotally connected to said receptacle by a pair of supporting links having their lower ends pivotally connected to said receptacle at the lower portion thereof and being pivotally connected adjacent their upper ends to said transverse bed frame members, an upper door panel and a lower door panel extending longitudinally across said receptacle open front so as to constitute a folding closure, said upper door panel being hingedly connected to said lower door panel with said lower door panel hingedly mounted on the base of said receptacle, guiding slots in said receptacle at opposite sides of said open front and guide means on said upper door panel slidably engaged in said receptacle guiding slots, and door supporting means operatively connected with said bed frame end members adapted to engage and support said doors in an intermediate position when said doors are lowered from a vertical position to a horizontal position and to raise said doors to said intermediate position from a horizontal folded position when said bed frame is swung away from a horizontal position to a vertical position about said supporting links.

8. In a foldaway bed construction as claimed in claim 7, said door supporting means comprising a pair of supporting lever arms, one of said arms being pivotally connected to each of said transverse end frame members adjacent one of said guide members, each of said lever arms having a first substantially straight portion extending from said pivotal connection and an arcuate end portion adapted to engage with and support said closure door panels in folded position, and flexible supporting means between each of said supporting arms and one of said bed frame end members adapted to support and actuate said supporting lever arms upon pivotal movement of said bed frame about said supporting links.

9. A foldaway bed construction as claimed in claim 8, including means adapted to ensure the horizontal folding of said foldable door portions comprising, a pair of elongated cam shaped lever members each pivotally connected inter-

mediate its length to one of said bed frame supporting links, each of said lever members having a first major portion extending from said pivotal connection to a sliding engagement with one of said bed frame guide members and a second minor portion extending in the other direction from said pivotal connection with the outer end disposed adjacent one of said door portions, said lever members being adapted to operate in conjunction with said bed frame and supporting links, whereby movement of said bed frame between the vertical and horizontal position, after said foldable door portions are in the intermediate closed position, actuates said second lever portion ends into an arcuate path following the descent of said upper door panel and into engagement with said door panel if said descent is impeded.

10. A foldaway bed structure, comprising, a supporting frame, a pair of spaced apart guiding tracks extending upwards and forwards from said supporting frame adjacent each end thereof, each of said guiding tracks having an upper outer terminus and a lower inner terminus, a rectangular bed frame having longitudinal side frame members and transverse end frame members, each of said transverse end frame members carrying a guiding member adjacent one end slidably engaged with one of said guiding tracks, a pair of elongated supporting links extending between said transverse end bed frame members and said supporting frame, each of said supporting links being pivotally connected adjacent one end to one of said end bed frame members beyond the centre line of said member with respect to said guiding member with the other end pivotally connected to said supporting frame adjacent the lower end of one of said guiding tracks, whereby the entire bed frame is adapted to be swung about said supporting links between a vertical position and a horizontal position with respect to said guiding frame with the guiding members guiding the inner edges of said bed frame between said upper outer termini and said lower inner termini of said guiding tracks during said swinging movement.

11. A bed structure according to claim 10, including a leg pivotally connected to the end of each transverse bed frame member remote from said guiding member for movement between a folded position parallel to said bed end frame member and a standing position perpendicular to said bed end frame member, a second pair of elongated connecting links each having one end pivotally connected to one of said first named elongated connecting links with the other end pivotally connected to one of said legs, whereby said legs are adapted to be moved between said folded position and said standing position by said second connecting links when the bed frame is moved between said vertical and horizontal positions.
